UNITED STATES PATENT OFFICE

SEPHUS F. BROWN, OF AMARILLO, TEXAS

PUMP VALVE

Application filed May 23, 1929. Serial No. 365,480.

This invention relates to oil well pumps, the primary object of the invention being to provide means to facilitate the removal of the standing valves forming a part of oil pumps, eliminating the necessity of drawing the tubing and the resultant waste of oil and cost of labor in pulling the tubing, when it becomes necessary to repair the standing valve of the pump.

10 An important object of the invention is to provide a device of this character wherein the working barrel of an oil pump may be dropped to engage the standing valve of the pump to lock the working barrel and standing valve together so that the standing valve may be readily removed from the tubing.

Another object of the invention is to provide means for automatically releasing the standing valve from the working barrel of the pump when the working barrel and standing valve are moved into the well and the standing valve strikes the bottom of the well, thereby permitting the working barrel to operate free of the standing valve.

25 With the foregoing and other objects in view which will appear as the description proceeds, the invention resides in the combination and arrangement of parts and in the details of construction hereinafter described

30 and claimed, it being understood that changes in the precise embodiment of the invention herein disclosed, may be made within the scope of what is claimed, without departing from the spirit of the invention.

35 Referring to the drawings:

Figure 1 is a longitudinal sectional view through a well tubing showing the working barrel and standing valve as connected.

Figure 2 is an enlarged elevational view 40 illustrating the standing valve and cage at the lower end of the working barrel, as connected.

Figure 3 is an enlarged elevational view 45 illustrating the standing valve and cage at the lower end of the working barrel, as disconnected.

Figure 4 is an enlarged elevational view 50 showing the cage and standing valve prior to the seating of the head of the standing valve in the cage of the working barrel.

Figure 5 is a sectional view through the cage on the lower end of the working barrel and the standing valve showing them connected for lifting the standing valve.

Figure 6 is a sectional view through the cage at the lower end of the working barrel and the standing valve showing the members disconnected.

Figure 7 is a sectional view taken on line 7-7 of Figure 5.

Figure 8 is a transverse sectional view through the cage at the lower end of the working barrel.

Figure 9 is a fragmental vertical sectional view through the cage at the lower end of the working barrel.

Figure 10 is a sectional view taken on line 10-10 of Figure 9.

Referring to the drawings in detail, the reference character 5 designates the well tubing of an oil pump in which the working barrel indicated by the numeral 6, operates. At the lower end of the well tubing 5, is a valve 7 known as the standing valve of an oil pump, the same including a cage or body portion 8 provided with longitudinal openings 9 and a seat against which the ball valve 10 operates in controlling the passage of oil through the valve.

In the present invention the standing valve 80 is provided with an extension 11 that extends upwardly from the upper end of the valve body, where it is provided with a transversely extended head 12 formed with inclined surfaces 13. The head is provided with a 85 downwardly extended portion 14, and an inclined portion 15 extending from the shank to the outer end of the head.

At the base of the shank 11 the body portion of the standing valve is formed with inclined surfaces 15 defining locking sections 16 that are adapted to fit into the notches 17 of the cage 18 that is secured to the lower end of the working barrel of the pump causing a twisting movement of the working barrel, 95 for purposes to be hereinafter more fully described.

A rectangular opening 19 is formed in the bottom of the cage 18 and is of a length to permit the head 12 to pass into the cage. Re-

cesses are formed in the bottom of the cage in such positions that they will receive the extension 14 and inclined portion 15 of the head 12 to lock the working barrel and standing valve together.

5 The operation of the device is as follows:

When it is desired to remove the standing valve to repair it or remove the paraffin therefrom, the working barrel is moved 10 downwardly to contact with the head 12, whereupon the inclined surfaces of the head 12 will move over the inclined surfaces of the notches 17 causing the working barrel to rotate bringing the opening 19 into registry 15 with the head 12 whereupon the head 12 moves into the cage 18. The working barrel is now given a quarter turn so that the head 12 will be extended transversely of the opening 19, or to a position as shown by Figure 7 20 of the drawings, locking the standing valve to the working barrel.

Should it be desired to replace the standing valve, the standing valve is positioned on the working barrel in a manner as shown by 25 Figure 1, and when the standing valve reaches the bottom of the well, movement of the working barrel into engagement with the standing valve will cause the inclined surfaces of the valve to cooperate with the inclined surfaces of the cage 18 resulting in a quarter rotation of the working barrel to bring the head 12 to a position in alignment with the opening 19, whereupon the working barrel may be elevated and removed, leaving 30 the standing valve in its operative position at the bottom of the well. The working barrel may now be operated in the usual and well known manner.

35 I claim:

40 In an oil well pump, a working barrel, a standing valve within the barrel, a shank extending upwardly from the standing valve, a transversely extended head formed integral with the shank, said head having downwardly sloping upper side edges, downwardly extended portions on the head near the shank, and formed along the lower edges of 45 the head, a cage having an elongated opening and having notches formed with inclined surfaces to accommodate the downwardly extended portions of the head, to prevent rotary movement of the cage with respect to the valve when the cage is being lifted, and means for rotating the cage when the cage is 50 dropped on to the standing valve to bring the head into registry with the elongated opening of the cage.

55 In testimony that I claim the foregoing as my own, I have hereto affixed my signature.

60 SEPHUS F. BROWN.
